UNITED STATES PATENT OFFICE.

HERMAN B. SANDE AND OTTO MOESSING, OF CHICAGO, ILLINOIS, ASSIGNEES TO
MOORE ELECTRIC CORPORATION, OF CHICAGO, ILLINOIS.

HAIR-CLIPPER.

1,396,530.

Specification of Letters Patent.

Patented Nov. 8, 1921.

Application filed January 18, 1919. Serial No. 271,805.

To all whom it may concern:

Be it known that we, HERMAN B. SANDE and OTTO MOESSING, former subjects of the Emperor of Germany, who have declared 5 our intention of becoming citizens of the United States, and residents of the city of Chicago, county of Cook, and State of Illinois, have invented certain new and useful Improvements in Hair-Clippers, of which 10 the following is a specification.

The invention relates to improvements in hair clippers and has for its object the provision of an improved construction of this character which is compact in form and 15 simple and efficient in operation.

Other objects will appear hereinafter.

The invention consists in the combinations and arrangements of parts hereinafter described and claimed.

20 The invention will be best understood by reference to the accompanying drawings forming a part of this specification, and in which,

Figure 1, is a side view of a hair clipper 25 embodying the invention,

Fig. 2, a top plan view of the same,

Fig. 3, a section taken substantially on line 3—3 of Fig. 1, and

Fig. 4, a section taken substantially on 30 line 4—4 of Fig. 3.

The preferred form of construction, as illustrated in the drawings, comprises the usual cutter head 5 having the usual reciprocating cutter blade 6 thereon and the usual 35 removable guard 7 for protecting said blade. The cutter blade 6 is operated by the usual rocker arm 8 connected by a link 9 with a lever 10 fulcrumed in an opening 11 leading into a casing 12 mounted upon the usual 40 handle 13 of the clipper. The lever 10 is provided with a central hub 14 surrounding its fulcrum, and the recess or opening 11 is provided with a central portion nicely fitting the sides of said hub, the sides of said 45 opening 11 being divergent or flaring forward and back from said central cylindrical portion to permit of oscillation of said lever. The lever 10 is provided at its inner end with a slot 15 engaging a crank pin 16 on a worm 50 wheel 17 mounted in casing 12, as shown,

and meshing with the usual worm 18. The usual socket 19 leads into casing 12 to permit of the insertion and connection of the usual flexible shaft with the worm 18. A removable closure plate 20 is provided to 55 permit of the assembling and inspection of the working parts.

By this arrangement it will be observed that the cutter blade 6 will be reciprocated in the usual manner by the operation of worm 60 wheel 17 in the usual manner. However, it will be observed that the lever 10, which serves as a connection between the worm wheel 17 and the cutter blade 6, entirely fills the opening in casing 12, thus preventing the 65 entry of hair clippings or other minute particles into the interior of casing 12. By this arrangement, the operating parts may be made to operate smoothly and without noise, and clogging thereof by the entry of the hair 70 clippings or other foreign matter is prevented.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the 75 scope of the appended claims.

Having described our invention, what we claim as new and desire to secure by Letters Patent is:—

A hair clipper comprising a cutting head; a reciprocating cutting blade on said head; a rocker arm operating said blade; a handle for said cutting head extending at an angle thereto; a casing on said handle; a worm 90 wheel in said casing; a worm in said casing meshing with said worm wheel; a socket for receiving a flexible shaft to drive said worm; a lever mounted on said casing and operatively connected with said worm wheel, there 95 being an opening in the inner end of said casing through which said lever passes, said opening being provided with a central cylindrical portion and divergent sides leading from the forward and rear sides of said 100

cylindrical portion; a lever fulcrumed in said opening and provided with a hub fitting the cylindrical portion thereof and said lever oscillating between said divergent sides; and a link connecting said lever with said rocker arm, substantially as described.

5 In testimony whereof we have signed our

names to this specification in the presence of two subscribing witnesses.

HERMAN B. SANDE.
OTTO MOESSING.
